(57) **CLAIM**

The ornamental design for headphone as shown and described.

DESCRIPTION

The file of this patent contains at least one drawing/photograph executed in color. Copies of this patent with color drawing(s)/photograph(s) will be provided by the Office upon request and payment of the necessary fee.

1. Headphone
2. Headphone
- 1.1: Front perspective view
- 1.2: Side view
- 1.3: Partial enlarged side view
- 1.4: Partial enlarged side view
- 1.5: Partial enlarged perspective view
- 1.6: Partial enlarged perspective view
- 1.7: Perspective view in a folded position
- 2.1: Front Perspective view
- 2.2: Side view
- 2.3: Partial enlarged perspective view
- 2.4: Partial enlarged perspective view
- 2.5: Partial side view
- 2.6: Partial side view
- 2.7: Perspective view in a folded position
